United States Patent

Des. 239,267
Patented Mar. 23, 1976

239,267

WHEEL

Millard Fillmore Harty, Jr., 4881 Kensington Road,
Bloomfield Hills, Mich. 48013

Filed Sept. 22, 1972, Ser. No. 291,304

Term of patent 14 years

Int. Cl. D12—16

U.S. Cl. D12—209

FIG. 1

FIG. 3

FIG. 2

FIG. 4

FIG. 1 is a front elevational view of a wheel showing my new design.

FIG. 2 is a top front perspective view thereof.

FIG. 3 is a fragmentary sectional view to an enlarged scale taken on the line 3—3 of FIG. 1.

FIG. 4 is a fragmentary sectional view to an enlarged scale taken on the line 4—4 of FIG. 1.

I claim:

The ornamental design for a wheel, substantially as shown.
